DESIGN FOR A CLASP LOOP FOR GARTERS OR THE LIKE

Floyd A. Knoll, Buffalo, N. Y., assignor to Condor
Products, Inc., Buffalo, N. Y.

Application August 4, 1934, Serial No. 52,816

Term of patent 14 years

To all whom it may concern:

Be it known that I, Floyd A. Knoll, a citizen of the United States, residing at Buffalo, Erie County, State of New York, have invented a new, original, and ornamental Design for a Clasp Loop for Garters or the like, of which the following is a specification, reference being had to the accompanying drawing, forming a part thereof.

In said drawing:

Fig. 1 is a front elevation of a clasp loop for garters or the like embodying my design.

Fig. 2 is a side elevation thereof.

Fig. 3 is a transverse section thereof, on line 3—3, Fig. 1.

In the drawing, the dominant feature of the design is found in the upper portion of the loop, such as above approximately the section line 3—3, including both the inner and outer contour and the aperture or loop at the top of the same.

I claim:

The ornamental design for a clasp loop for garters or the like, substantially as shown and described.

FLOYD A. KNOLL,
